WINDOW OPERATING MECHANISM

Daniel L. Chandler, Salem, George W. Ewing, Peabody, and Frank H. Walker, Salem, Mass., assignors to Aresee Company Inc., Salem, Mass., a corporation of Massachusetts

Application February 15, 1940, Serial No. 319,036

3 Claims. (Cl. 268—124)

Our present invention relates to electrical door driving mechanism, and more particularly to a particular means for varying the speed of an alternating lever which actuates the raising and lowering mechanism of an automobile window, the alternating lever being actuated by a crank connecting with an electrical motor.

This invention is a continuation in part of our co-pending application entitled "Electrically operated window," Serial Number 302,082, filed October 31, 1939.

In our co-pending application, the window actuating lever, which is the same in our present application, carries certain finger members. One of these fingers is pivoted above the pivot of the actuating lever and the other finger is pivoted below the said lever pivot. Each of said fingers when the said lever is thrown to its extreme position is out of contact with certain portions of the mechanism with which it engages on its forward movement.

When a continuous drive is provided, as in our continuous electrical apparatus, as set forth in the said co-pending application, the engagement of the said fingers with the raising and lowering mechanism produces an objectionable clash which is due to the contacting of the fingers with such apparatus.

Our present application is concerned with an improved drive which quickly takes up this lost motion and gently engages the said fingers with the raising and lowering apparatus in a smooth and silent manner thereby eliminating the objectionable noises.

As the present specification progresses, we will point out in further detail just how this is accomplished.

The principal object of our present invention is an improved drive for electrically operated automobile window raising and lowering mechanism;

Another object is a crank mechanism adapted to vary the speed of the crank-throw changing the speed of crank thrust at predetermined points throughout a complete cycle, and

Other objects and novel features comprising the construction and operation of our invention will appear as the description of the device progresses.

In the drawings illustrating the preferred embodiment of our invention:

Fig. 1 is a fragmentary side elevation of the inside of an automobile door showing the driving mechanism as connected with the window raising and lowering actuating lever, certain por-

tions of the door panel being broken away to show parts of the inner mechanism;

Fig. 2 is a fragmentary broken away elevation more particularly showing the cam slot in the window raising and lowering mechanism;

Fig. 3 is a fragmentary side elevation of the window raising and lowering apparatus, portions of the glass sash being broken away for convenience in illustration. In this figure the apparatus is viewed from the opposite side with respect to Figs. 1 and 2;

Fig. 4 is a fragmentary view of the drive shown in Fig. 1 but viewed from the rear;

Fig. 5 is a view similar to Fig. 4 but showing the drive mechanism slightly advanced from the point shown in Fig. 4, and

Fig. 6 is a cross-section taken on the line 6—6 of Fig. 5 showing the method of forming a groove for the belt in the periphery of the sheave member.

As previously stated, our present invention is an improvement of the drive mechanism, as set forth in our co-pending application. However, this improved drive may be used for other similar requirements.

In Fig. 3 we will briefly describe the window raising and lowering mechanism so that the present drive improvement will be clearly understood.

At 10 we have indicated an automobile window pane vertically slidable in conventional guideways 11. The window pane 10 is elevated and lowered by means of arms 12 and 13 which carry rollers on their free lower ends and said rollers are engaged in channel members 14 attached to the lower side of the window pane edge member 15. The other ends of the arms 12 and 13 terminate in attached pinion members 16 and 17 respectively being interlocked by means of the gear teeth shown. The pinion 17 is further provided with a large segment 18, the outer periphery of which is provided with a plurality of V shaped teeth 19 spaced away from each other by extended slots 20 the sides of which are parallel. The segment 18 and pinions 16 and 17 are mounted on a base member 21 which is mounted on the inside door panel 22 at points 23.

Radially disposed in the base member 21 are cam slots 24 and 25.

Pivoted at 26 to the base member 21 is an oscillating window actuating lever 27, the lower end of which extends to a point below the bottom of the lowermost position of the window pane 10 and connects with the reciprocating lever 28.

Pivoted at 29 and 30 respectively are the finger

members 31 and 32. By inspection, it will be noted that the forward ends of the fingers 31 and 32 are V shaped to engage the V sides of the teeth 19 on the segment 18.

With the setting of the apparatus, as shown in Fig. 3, the lower finger 32 is at the end of its stroke and engaged in the slot 20 while the upper finger 31 is at its extreme rearward position. When the lever 27 is reversed by the reciprocating lever 28 and thrown to the right, as viewed in Fig. 3, the finger 32 is pulled out of the slot 20 and the V end of the finger 31 engages against the upper side of the V tooth 19 directly in front of the finger 31. This lost motion period between the point of the finger 31 and its engagement with the upper side of the tooth 19 produces a clash which is noisy and undesirable in an apparatus of this kind. When the lever 27 is returning from the right extreme the same action takes place on the finger 32.

As set forth in our co-pending application, the setting of the fingers, with respect to the contacting side of the teeth 19, is controlled by the reversing slide 33 which is actuated manually. The electrical contacts 34 are connected by the common connector 35 in the same manner as in the co-pending application above referred to.

On the back side of the fingers 31 and 32 is provided the cam studs 36 which engage against the sides of the cam slots 24 and 25 in the base member 21 and guide the fingers 31 and 32. These cam slots 24 and 25 are radially disposed to the segment 18.

Below the window pane 10 and inside the door panel 22, we have mounted our improved drive which comprises an electric motor 40 which is connected to a sheave 41 by means of a flexible belt 42.

The sheave 41 is provided with a crank lever 43, one end of which is pivoted to the reciprocating lever 28, at 44. The crank lever 43 is journaled in one of the spokes of the sheave by means of the shaft 45. On the inside of the shaft 45 remote from the lever 43 is mounted another lever 46. The levers 43 and 46 are both keyed to the shaft 45 by means of the key 47. On the free end of the lever 46 is pivoted a cam roller 48.

Secured to the support 49 is an internal cam comprising an outer member 50 and an inner member 51. Between the members 50 and 51 is provided a cam track 52 within which the cam roller 48 travels.

In Fig. 1 and in Fig. 4, the cam roller 48 is positioned at the high point of the cam. In this position, the lever 28 is at its farthermost swing to the left, as viewed in Fig. 1. In this position, the finger 32 is about to move toward the V shaped teeth 19. As the motor 40 turns the sheave 41, in the direction of the arrow, in Fig. 1, the cam roll 48 in the cam path 52 is drawn inwardly toward the pivot point of the sheave 41 to a point approximating a position 53. As the cam roll 48 follows the cam path 52 inwardly toward the pivot point of the sheave 41, the movement of the reciprocating lever 28 is accelerated in speed from what would otherwise have been its normal movement. As a consequence, the lever 27 is swung back at a corresponding accelerated speed which brings the point of the finger 32 over to the side of the V shaped tooth 19 quickly. At this point of movement of the finger 32, the cam roll 48 reaches its lowest point on the cam path 52 and the speed of the said finger slows up bringing the pointed end into contact with the side of the

V tooth 19 at a reduced speed and thereby obviating the clash which otherwise will result.

The cam roll 48 travels along the cam track 52 in the manner shown in the drawing half way around or until the finger 32 has reached its innermost position in the segment slot 20 and is ready to return. At this position, the upper finger 31 is in its most rearward position comparable to the same position of finger 32, at its start of the above described movement. At this time the cam roll 48 has reached a position approximating 60 on the cam track 52. Again the cam track 52 moves in toward the pivot center of the sheave 41 and the finger 31 moves quickly toward the V tooth 19 in the same manner as did the finger 31 gently engaging the side of the V tooth 19 and continuing on at a reduced speed to the slot 20.

The cam track 52 is so proportioned with respect to the pivot center of the sheave member 41 that the speed of the fingers after having quickly taken up the lost motion between the fingers 31 and 32 and the teeth 16, is approximately uniform.

Normally, the movement of the reciprocating lever 28 is speeded up at the two points located at ninety degrees to horizontal plane through the pivot point of the sheave 41 and the lever shaft 45. With our arrangement of the cam track 52 and the levers 43 and 46, the movement of the lever 28 is maintained at a constant speed at all times except that point when the point of the fingers 31 and 32 are moving into contact with the sides of the V shaped teeth 19.

The drive between the sheave 41 and the pulley on the motor 40 is indicated at 42. This belt is composed of rubber of a very high tensile strength similar to that used on the outer tread of automobile tires. The belt 42 is under tension at all times and because of its elasticity and tensile strength provides a very flexible and efficient means for driving the sheave 41.

The sheave 41 is preferably made of sheet metal. The periphery is provided with a plurality of alternately bent flanges 65, the belt 42 riding between these flanges, as shown in Fig. 6.

It will thus be seen that we have designed a drive in which the motor runs at a continuous given speed thereby imparting a constant rotational speed to the sheave 41, but due to the cam track 52 and the crank levers 43 and 46, the crank lever 28 is maintained, in either direction, at a constant speed excepting that period in which the cam roll 48 moves quickly toward the sheave center, the result of which is to speed up the movement of the lever 28, at such point. Throughout the rest of the travel of the cam roll in the cam path 52, the reciprocating lever 28 is maintained at a constant rate of movement compensating for the ever changing position of the crank lever 43 due to the cam path 52. The result of such compensated movement of the reciprocating lever 28 is to impart to the window raising and lowering mechanism a smooth continuous speed movement directly imparted from a reciprocating lever which is rotating at a continuous speed thereby eliminating the jerking motion otherwise resulting.

Having thus described our invention what we claim as new is:

1. In combination with a window raising and lowering mechanism having a base member and a segmental member pivoted thereon with

pointed teeth located on its periphery, and an operating lever having V pointed cam fingers pivoted thereon with back portions engaging with a cam finger slide slidably mounted on said base member, the V pointed portions of said cam fingers engaging against the V sides of said V pointed teeth on said segmental member, an oscillating lever pivoted to said operating lever, the said oscillating lever having a lost motion period at the beginning of each oscillating movement, a continuous rotating sheave, a crank lever arm pivoted to the side of said sheave, a cam track located adjacent said sheave and fixed against rotation, a cam lever and cam roll fixed to said crank lever arm, said cam track having a high and a low point with respect to the central point of said sheave, a reciprocating lever connecting with said crank lever arm and said oscillating lever.

2. In combination with a window raising and lowering mechanism having a base member and a segmental member pivoted thereon with V pointed teeth located on its periphery, and an operating lever having V pointed cam fingers pivoted thereon with back portions engaging with a cam finger slide slidably mounted on said base member, the V pointed portions of said cam fingers engaging against the V sides of said V pointed teeth on said segmental member, an oscillating lever pivoted to said operating lever, the said oscillating lever having a lost motion period at the beginning of each oscillating movement, a continuous rotating sheave, a crank lever arm pivoted to one side of said sheave, a reciprocating lever connecting said crank arm with said oscillating lever, a fixed cam track located adjacent said sheave, a cam and cam lever, said cam lever fixed to said reciprocating

arm lever being pivoted to said sheave, a cam track engaging with said cam, said cam track having a path of varying radial distance from the rotational center of said sheave for the purpose of varying the pivoted position of said reciprocating arm lever with respect to the center of rotation of said sheave.

3. In combination with a window raising and lowering mechanism having a base member and a segmental member pivoted thereon with V pointed teeth located on its periphery, and an operating lever having V pointed cam fingers pivoted thereon with back portions engaging with a cam finger slide slidably mounted on said base member, the V pointed portions of said cam fingers engaging against the V sides of said V pointed teeth on said segmental member, an oscillating lever pivoted to said operating lever, the said oscillating lever having a lost motion period at the beginning of each oscillating movement, a continuous rotating sheave, a crank pivoted to one side of said sheave, a cam lever pivoted to the opposite side of said sheave, said crank and cam lever being fixed together and pivoted through said sheave as a unit, a fixed cam track located adjacent one side of said sheave, a cam pivoted to said cam lever and engaged in said cam track, a pivoted reciprocating lever connecting said oscillating lever with said crank, means located in said cam track for varying the radial distance between the rotational center of said sheave and the oscillating end of said crank.
